F. S. LEAVITT AND E. A. STAPLES,
IDENTIFYING MEANS FOR PNEUMATIC DISPATCH TUBE CARRIERS,
APPLICATION FILED JULY 29, 1921.

1,423,440.

Patented July 18, 1922.

UNITED STATES PATENT OFFICE.

FRANK S. LEAVITT, OF MELROSE, AND ERNEST A. STAPLES, OF DORCHESTER, MASSACHUSETTS, ASSIGNEES TO ATLAS DEVICES COMPANY, INC., A CORPORATION OF NEW YORK.

IDENTIFYING MEANS FOR PNEUMATIC-DISPATCH-TUBE CARRIERS.

1,423,440.

Specification of Letters Patent.

Patented July 18, 1922.

Application filed July 29, 1921. Serial No. 488,313.

To all whom it may concern:

Be it known that we, FRANK S. LEAVITT, a citizen of the United States, resident of Melrose, county of Essex, State of Massachusetts, and ERNEST A. STAPLES, a citizen of the United States, resident of Dorchester, and county of Suffolk, State of Massachusetts, have invented certain new and useful Improvements in Identifying Means for Pneumatic-Dispatch-Tube Carriers; and we do hereby declare the following to be a full, clear, and exact description of the invention, such as will enable others skilled in the art to which it appertains to make and use the same.

This invention relates to carriers for pneumatic dispatch tube systems, and involves the provision of identifying means for the carriers so that they may be readily distinguished one from another, or classified and identified with particular outlying points or stations in the system.

Pneumatic tube systems usually provide communication between a number of outlying stations and a central station, and also in some instances between outlying stations and between substations of the central station. Taking the familiar example of a pneumatic dispatch tube system for a department store, the various counters throughout the store are all in communication by separate lines of tubes with a central station to which the carriers are sent with sales slips and cash, credit slips, or other records, where the transactions are recorded, or change made and inserted in the carriers which are then despatched to the counters from which they were sent. The lines of tubes for transmitting the carriers from outlying stations to the central station commonly have their terminals or discharge ends in the latter banked over a desk, at which also the sending tubes from the central station to the outlying stations are similarly arranged adjacent the receiving tubes. The carriers are received at the desk from all outlying stations by an operator or clerk who carries out the necessary transactions, and then sends the carriers back to the respective outlying stations from which they were received.

In order that the carriers may be identified with the particular outlying stations

from which they were sent, it is necessary that they bear some mark of identification so that the clerk in the central station can readily determine to which stations the carriers are to be returned. It has heretofore been the common practice to mark the carrier with identifying characters usually by stamping the body or shell of the carrier with identifying numerals. Such means of identification has the disadvantage that the markings cannot readily be changed. Also where the body or shell of the carrier is stamped with identifying characters, they are usually difficult to find and not easily read, becoming more and more illegible as the markings are subjected to wear on this portion of the carrier.

In accordance with the present invention the carrier is provided with identifying means secured to the ends of the carrier, in which position it is at once readily visible to the operator, as well when the carriers are lying on a desk as when they are picked up by the operator to be returned to outlying stations. The identifying means are conveniently numbered, and one scheme of classification of the carriers is to mark all carriers at each of the outlying stations with the same number. For example, in a department store all carriers at one outlying station or counter would bear the number 7 and all carriers at another counter would be marked 15, etc. In the central station the sending tubes for returning the carriers to their respective outlying stations are correspondingly numbered, and so the carriers may be speedily despatched by inserting them in the lines bearing like numbers.

The identifying device of the present invention is set in recesses one at each end of the carrier, or in recesses in buffer heads at the ends of the carrier, in each of which it is removably secured, and is provided with suitable identifying characters. These characters are, therefore, not only readily seen, but they are protected against injury or obliteration through handling of the carrier and the devices may also easily be removed to change the identifying characters.

Where the identifying device is employed in connection with a carrier having buffer heads at its ends provided with recesses,

the device is preferably fastened in place in each recess by the means securing the buffer heads to the body of the carrier. For example, the securing means for each buffer head may 5 include a plate or washer fitted in its recess, in which case the identifying device is fastened in place by a clip, secured by the plate, the clip having upstanding ends which are bent over the identifying device 10 to fasten it in place in the recess. Preferably the identifying device consists of a plate carrying identifying characters on its surface, the plate fitting in the recess on top of the plate or washer for securing each 15 of the buffer heads at the ends of the carrier.

In the specific embodiment of the invention described hereinafter the carrier is of the type comprising a shell or body portion, 20 the ends of which are provided with buffer heads. The buffer heads have recesses in their ends in each of which a washer is fitted, and appropriate means are provided for tightening the washers against the inside of 25 the shell for securing the buffer heads to the carrier. The identifying device, one of which is inserted in each of the recesses in the buffer heads at the ends of the carrier consists of a plate carrying identifying numerals and a sheet of transparent material 30 covering the plate to protect its surface bearing the identifying character against wear. In each of the recesses is a clip, secured by the washers therein, for fastening the identifying device in place by bending over the ends of the clip so that the devices may easily be removed and other devices bearing a different identifying character inserted.

The invention is illustrated in the accompanying drawings, in application, as for example, to a pneumatic dispatch tube carrier having a buffer head, in which—

Figure 1 represents a type of pneumatic dispatch tube carrier having buffer heads 45 at the ends thereof, the carrier being shown partly open;

Figure 2 is a longitudinal sectional view of the carrier, illustrated in Figure 1, showing the method of attaching the identifying device in the ends of the buffer heads;

Figure 3 is an end view of the carrier showing the identifying device set in the buffer head and the clips for holding it in place;

Figure 4 is a view similar to Figure 3 with the identifying device removed;

Figures 5 and 6 illustrate the parts comprising the identifying device, Figure 5 being a disc of transparent material and Figure 6 a plate provided with identifying characters;

Figure 7 shows a plate provided with screw holes, one of which is employed for fastening each buffer head to the body of 65 the carrier;

Figure 8 is a perspective view of the clip for securing the identifying device in place, and

Figure 9 is a section of the body of the carrier taken along the line 9—9 of Figure 2. 70

The carrier consists of a shell or body portion 10 having at its ends buffer heads 11, the latter being made of felt or any other soft, resilient substance. The body portion of the carrier consists of two cylinders 75 12 and 13 fitted together, or telescoped, and movable relative to each other, the cylinders having openings 14 and 15 respectively, which may be brought into and out of registry to open and close the carrier. The 80 outer cylinder 13 is provided with a stop 16 which is engaged by the notches 17 and 18 in the inner cylinder to limit the relative movement of the cylinders and fix their extreme open and closed positions. 85

Each of the buffer heads 11 is provided with a recess 19 in which fits a plate 20 having screw holes 21. Passing through the screw holes 21 and the buffer 11 are screws 22 the ends of which screw into the bar 23 90 on the inside of the body portion of the carrier. The buffer 11 is thus held on the end of the body portion of the carrier between the plate 20 and the bar 23. The plate 20 also serves as part of the fastening means 95 for the identifying device in each of the recesses 19 in the buffer heads 11. Secured between the plate 20 and the bottom of the recess 19 is a clip 24 having upstanding end pieces 25 extending above the plate 20. 100 Fitted between these end pieces 25 and on top of the plate 20 is a disc 26 carrying the identifying device, as for example, a paper disc having identifying numerals printed thereon, and over this disc is placed a disc 105 27 made of transparent material, preferably non-breakable material, such as celluloid, through which the identifying characters are visible. The discs 26 and 27 are fastened in place simply by bending the upstanding end pieces 25 of the clip 24 over the edges of the discs. 110

It will be evident that the identifying device, consisting of the discs 26 and 27, which are made to closely fit the recess 19, 115 are readily inserted in the latter and fastened in place by bending over the upstanding ends 25 of the clips. When it is desired to insert new identifying devices to replace a set in the carrier, it is simply necessary to 120 bend back the upstanding ends 25 of the clips, pry out discs 26 and 27, and insert a new disc for the disc 26, replace the transparent disc 27 and bend the ends 25 of the clips over the discs. 125

We claim:

1. A pneumatic dispatch tube carrier comprising a body portion and a buffer head at the end thereof, said buffer head having a recess, means in said recess for securing the 130

buffer head to said body portion, and an identifying device fastened in the recess by said buffer securing means.

2. A pneumatic dispatch tube carrier comprising a body portion and a buffer head at the end thereof, said buffer head having a recess in its end, means in said recess for securing the buffer head to said body portion, an identifying device for the carrier consisting of a plate carrying identifying characters, and a clip fastened in the recess by said buffer securing means for holding said plate in the recess.

3. A pneumatic dispatch tube carrier comprising a body portion and a buffer head at the end thereof, said buffer head having a recess in its end, means for securing the buffer head to said body portion including a plate fitted in said recess, a clip secured by 20 said plate, and a plate carrying identifying characters secured in the recess by the ends of said clip.

4. A pneumatic dispatch tube carrier comprising a body portion and buffer heads at 25 the ends thereof, said buffer heads having recesses in their ends, plates fitted in said re-

cesses, means for tightening said plates against the inside of the carrier for securing the buffer heads to the body portion, clips secured by said plates, and plates carrying 30 identifying characters held in the recesses by said clips.

5. A pneumatic dispatch tube carrier comprising a body portion and buffer heads at the ends thereof, said buffer heads having 35 recesses in their ends, washers fitted in said recesses, means for tightening said washers against the inside of the carrier for securing the buffer heads to the body portion, clips secured by said washers, and an identifying 40 device for insertion in each of said recesses consisting of a plate carrying identifying numerals, a sheet of transparent material for covering said plate to protect the surface thereof, and clips in each of said recesses secured by the washers therein for fastening the identifying devices in place in the recesses by bending over the ends of the clips. 45

In testimony whereof we affix our signatures.

FRANK S. LEAVITT.
ERNEST A. STAPLES.
